UNITED STATES PATENT OFFICE.

JOHN L. NICHOLSON, OF CHICAGO, ILLINOIS, ASSIGNOR TO AMERICAN ARCH COMPANY, OF NEW YORK, N. Y., A CORPORATION OF DELAWARE.

LOCOMOTIVE-BOILER FIRE-BOX.

1,229,376.

Specification of Letters Patent. Patented June 12, 1917.

Application filed December 28, 1915. Serial No. 69,017.

To all whom it may concern:

Be it known that I, JOHN L. NICHOLSON, a citizen of the United States, and a resident of Chicago, county of Cook, and State 5 of Illinois, have invented certain new and useful Improvements in and for Locomotive-Boiler Fire-Boxes, of which the following is a specification.

My invention relates to improvements in 10 locomotive boiler furnaces, and has special reference to improvements in the refractory arches of such furnaces. The invention is applicable to refractory arches or baffles which are supported by water-circulating 15 arch tubes and also to those supported from the side sheets of the furnace or firebox.

There are two generally approved ways 20 of installing an arch in a locomotive firebox. The lower end of the arch is either placed in direct abutment with the lower part or throat of the flue sheet, or is spaced away from the flue sheet to provide cinder openings. Such openings prevent the accumulation 25 of cinders on the arch and in the lower flues of the boiler, but allow relatively cold air to pass direct from the grate to the flues. For many years railroad engineers have been in conflict as to whether the lower end 30 of the arch should be allowed to abut against the flue sheet, without cinder openings; or whether the obvious detriment of cold air in the lower flues is not overbalanced by the advantages of cinder openings at the lower end of the arch.

35 By means of my invention I have very simply and effectively solved the problem by providing the cinder openings which all engineers regard as desirable and at the same time overcoming the objections to such 40 cinder openings.

My invention will be readily understood on reference to the drawings that form part of this specification, in which:—Figure 1 is a vertical longitudinal section of a locomotive firebox embodying my invention:—Fig. 2 is a horizontal section thereof substantially on the line X—X of Fig. 1;—Fig. 3 is a vertical transverse section substantially on the line Y—Y of Fig. 1;—Fig. 4 is a perspective detail of the lower end of the

arch;—and Fig. 5 is a sectional detail illustrating a modified form of my invention.

The typical locomotive boiler firebox shown in the drawings comprises the flue sheet, 2;—the side sheets, 3, 3;—the crown sheet, 4;—the rear sheet, 5;—and, the grate, 6. The other familiar parts shown are, the boiler shell, 7, forming water legs around the firebox; and the flues, 8; and the group of arch tubes, 9, which last extend from the throat sheet, 2', to the upper part of the rear sheet, 5.

As a first step in my invention, I place a mass, 10, of refractory material against the throat sheet, 2', supporting the same, preferably by means of a step or bracket, 11, on the throat sheet, 2', at the forward end of the grate, 6. This refractory mass extends from side to side of the firebox and upward to the level of the lowermost flues, 8. As 65 shown, the mass incloses the lower parts of the arch tubes. While the mass may be applied in a plastic state and later burned by the fire on the grate, I prefer, as here shown, to form it of a number of separate refractory bricks shaped to fit the parts, 2', 11, and 9. Against the upper rear face, 10', of the mass, 10, I place arch struts or spacing bricks, 12. These serve to space the refractory arch, A, rearwardly, away from the 70 mass, 10, and the flue sheet. I use such struts with arches of all forms, whether the arches are supported upon arch tubes or upon the side sheets of the firebox. When arch tubes are present, the struts, 12, are fitted 75 thereto and rest thereon; and are thus effectively held against lateral displacement. The arch body, A, shown in the drawings, is of the sectional type; that is, composed of a large number of refractory bricks, A', which rest 80 upon the arch tubes. The joints between the several longitudinal rows of arch bricks, A', are upon the tubes, and each strut, 12, serves as the abutment for two of the longitudinal rows. By this construction I provide a cinder opening, B, at the lower end 85 of the arch, A. This opening may be said to extend from side to side of the firebox, although, as shown, it is divided into several parts by the struts or bricks, 12.

In the operation of the furnace a high temperature is attained, and in consequence all of the refractory bricks, 10, 12 and A, are kept in a state of substantial incandescence. The presence of the arch, A, causes most of the products of combustion, from the fuel on the grate, to follow the indirect course around the end of the arch, but some of the products pass directly to the flues 10 through the cinder openings, B. Obviously, in the case of my invention, all of the walls of the cinder openings are composed of hot refractory material and the products are therefore raised to a high temperature before reaching the flues. The refractory mass, 10, is so considerable as to thus insure substantially complete combustion of the products which escape through the cinder openings and the attainment in the lower flues of temperatures substantially equaling the temperatures of the products which enter the upper flues.

Combustion on the front end of a grate, when covered by an arch is not as active as upon the freer parts of the grate; and much of the air which is drawn through the front end of the grate is not consumed, nor raised to a high temperature, and, if it were not for the presence of the highly heated mass, 30, the products would enter the lower flues at temperatures so low as to prevent the expansion and contraction thereof in harmony with the upper flues. That is what occurs in the case of the ordinary arch which has 35 cinder openings, and is the chief cause of leaky flues and damaged flue sheets. My invention completely overcomes this difficulty by insuring temperatures quite as high as can be attained with an arch that has no 40 cinder openings and yet in securing this advantage I do not sacrifice the advantage of the cinder openings, to wit, the keeping of the arch and flues free from accumulations of cinders.

45 The usual difficulty is accentuated when the firebox has a throat sheet that slants rearwardly and over which the products must pass to reach the flues. Obviously such a sheet extracts even more heat from 50 the products than does a vertical throat sheet. By my invention this frequently encountered disadvantage is turned into an advantage, for the slanting throat sheet furnishes a better support for the refractory 55 mass and a more secure means of attachment than can be obtained with a vertical throat sheet; and, furthermore, the mass arranged upon a slanting throat sheet does not overlap the grate or reduce the grate area.

60 It will be noted that the top, 10^b, of the refractory mass, 10, slants, or is rounded, from the flue sheet toward the grate and does not present a surface upon which cinders can 65 accumulate; as would be the case if the top of the mass were flat. A further advantage

of my construction is that the gases which rise from the grate toward the cinder opening are not permitted to flow directly to the flues, for the mass, 10, is angled or bowed rearwardly and acts to deflect or baffle the gases below and in the cinder opening, the flame travel, and hence the efficiency of the firebox being considerably increased.

70 My invention is of special utility where the throat sheet of the firebox is very narrow and the lower parts of the arch tubes are bent upward to provide fuel clearance below the arch at the front end of the grate. Such a case is shown in Fig. 5 in which a narrow throat sheet, 2^a, and bent arch tubes, 9^a, 80 serve to support the refractory mass, 10^a, fully as well as in the form shown in Figs. 1 to 4. I do not herein claim the clearance increasing construction shown in Fig. 5, 85 having both described and claimed the same in a companion application of even date herewith, Serial No. 69,016.

Having thus described my invention, I claim as new and desire to secure by Letters Patent:—

90 1. A locomotive firebox, in combination with a refractory mass covering and protecting the throat sheet thereof and terminating at the lower edge of the flue sheet, and a refractory arch springing substantially from said mass but separated therefrom by a cinder opening, said arch terminating short of the rear wall of the firebox and there being a main gas passage rearward of the arch, the function of said mass being to 95 heat the gases which pass through said cinder opening and protect the flues as described.

100 2. A locomotive firebox having a slanting throat sheet, in combination with a refractory mass covering and resting upon and protecting said throat sheet and terminating at the lower edge of the flue sheet, and a refractory arch springing substantially from said mass but separated therefrom by a 105 cinder opening, said arch terminating short of the rear wall of the firebox and there being a main gas passage rearward of the arch, the function of said mass being to heat the gases which pass through said cinder opening and protect the flues as described.

110 3. A locomotive firebox, its grate, throat sheet and water circulating tubes, in combination with a refractory mass arranged against said throat sheet and extending from 12 the grate to the lower flues, and a refractory arch supported by said tubes and springing substantially from said mass, but separated from said mass by a cinder opening, said arch terminating short of the rear wall of 12 the firebox and there being a main gas passage rearward of the arch, substantially as and for the purpose described.

115 4. A locomotive firebox, its throat sheet, and water circulating tubes springing there- 1:

from, in combination with a refractory mass upon said throat sheet extending both above and below said tubes, and terminating at the lower edge of the flue sheet, and a refractory arch supported by said tubes and springing substantially from said mass, but separated from said mass by a cinder open-

ing, said arch terminating short of the rear wall of the firebox and there being a main gas passage rearward of the arch, substantially as and for the purpose described. 10

In testimony whereof, I have hereunto set my hand this 6th day of December, 1915.

JOHN L. NICHOLSON.
